(57) **CLAIM**

The ornamental design for a ball retriever, as shown and described.

DESCRIPTION

FIG. 1 is a perspective view of my ball retriever, showing

my new design, with a ball shown in the retriever in dotted lines;

FIG. 2 is a bottom view of the retriever of FIG. 1;

FIG. 3 is a front view thereof;

FIG. 4 is a right side view thereof;

FIG. 5 is a rear view thereof;

FIG. 6 is a left side view thereof;

FIG. 7 is a top end view thereof;

FIG. 8 is a perspective view of a second embodiment of the invented ball retriever, showing a ball in dotted lines;

FIG. 9 bottom view of the embodiment of FIG. 8;

FIG. 10 is a front view of the embodiment of FIG. 8;

FIG. 11 is a top end view of the embodiment of FIG. 8;

FIG. 12 is a right view of the embodiment of FIG. 8;

FIG. 13 is a rear view of the embodiment of FIG. 8;

FIG. 14 is a left side view of the embodiment of FIG. 8;

FIG. 15 is a perspective view of a third alternative embodiment of the invented ball retriever, shown in the retracted position, and showing a ball therein in dotted lines;

FIG. 16 is a bottom view of the embodiment of FIG. 15;

FIG. 17 is a front view of the embodiment of FIG. 15, shown in the extended position;

FIG. 18 is a right side view of the embodiment of FIG. 15;

FIG. 19 is a rear view of the embodiment of FIG. 15;

FIG. 20 is a left side view of the embodiment of FIG. 15; and,

FIG. 21 is a top end view of the embodiment of FIG. 15.
